Patented Aug. 31, 1971

221,691

COMBINED LOOSELEAF RING BINDER, RADIO
AND COMPARTMENTED PENCIL BOX OR
SIMILAR ARTICLE

Philip Leland Gammon, 7701 Granger Road,
Richmond, Va. 23229

Filed May 12, 1970, Ser. No. 22,940

Term of patent 14 years

Int. Cl. D14—03; D19—04, 99

U.S. Cl. D56—4

FIG. 1

FIG. 2

FIG. 3

FIG. 1 is a perspective view of a combined looseleaf ring binder, radio and compartmented pencil box or similar article, showing my new design in closed position;

FIG. 2 is a side elevational view;

FIG. 3 is an opposite side elevational view;

FIG. 4 is an end elevational view;

FIG. 5 is an opposite end elevational view; and

FIG. 6 is a perspective view thereof in open position and with two of the compartment doors open.

I claim:

The ornamental design for a combined looseleaf ring binder, radio and compartmented pencil box or similar article, as shown.
